PHONOGRAPH HORN FOR PORTABLE PHONOGRAFS

Richard Hal Coffren, Washington, D. C.

Application April 23, 1940, Serial No. 331,248

8 Claims. (Cl. 274—2)

The object of my invention is to provide a novel horn for portable and other phonographs which better reproduces the tones of records than horns heretofore devised, which is very compact and is especially adapted for use on portable phonographs which have cabinets of relatively small size and shallow depth.

It is an especial object of my invention to provide a horn which will modify the vibrations of bass notes so that a more accurate and beautiful reproduction of the original recording may be obtained than has been possible with horns of other types.

It is also an object of my invention to have the tone arm concealed by being disposed under the platform of the phonograph and to provide a construction that will so modify the bass notes reproduced as to prevent "blasting" and undesirable vibrations; and to provide a tone modifier or visible horn on the motor board of such shape that it will take up relatively little vertical room and will partly overlie the turntable whereby to make it possible to produce a compact portable phonograph in a compact and relatively small cabinet, and which will reproduce tones with unusual clearness.

I attain these and other objects of my invention by the mechanism illustrated in the accompanying drawings, in which—

Figure 1 is a perspective view of the invention installed in a portable phonograph;

Fig. 2 is a horizontal section on line 2—2 of Fig. 3;

Fig. 3 is a vertical section on line 2—2 of Fig. 1;

Fig. 4 is a vertical section of a modification of the invention on a line similar to section line 3—3 of Fig. 2;

Fig. 5 is a view partly in horizontal section and partly in bottom plan of a modification of the invention in which a longer tone arm is provided, and

Fig. 6 is a vertical section on line 6—6 of the modification shown in Fig. 5.

Like numerals designate like parts in each of the several views.

Referring to the accompanying drawings, there is illustrated a portable phonograph cabinet 1, having the customary hinged cover 2, handle 3, platform 4, turntable post 5, turntable 6, reproducer 7 and reproducer arm 8. The cover is supported in the slanting position shown in Fig. 1 by a bracket 2a and pivotally mounted slotted metal arm 2b. The cabinet may be fastened by any suitable fastening means for transporta-

tion. All of these elements are conventional except that in applicant's cabinet, the cover 2 is of relatively greater depth than is usual in portable phonograph cabinet covers.

Mounted on the phonograph platform or motor board 4 is a tone modifier or visible horn comprising like forwardly expanding or slanting horn walls 11a supporting a flat horn top 11, upwardly curved rear walls 11b continuing in a flat top wall 11c extending parallel with the motor board and extending only part way over the turntable so as not to interfere with the necessary swing range of movement of the reproducer arm.

The reproducer arm 8 is in communication with a concealed wooden tone arm or horn 9 substantially square in cross section and disposed beneath and concealed by the motor board a portion of the motor forming the upper wall of said tone arm, as shown in Figs. 3 and 4. Tone arm 9 extends parallel with the adjacent side of the cabinet and curves at the rear and terminates in a rear tone arm section 9a disposed parallel to the rear wall of the cabinet and at right angles to the tone arm 9. The tone arm sections 9 and 9a gradually expand in cross-sectional area from the reproducer horn to their mouth. Rear section 9a of the tone arm has an upwardly curved end portion 9b and an oppositely positioned upwardly inclined wall 10 which terminates in the opening 10a of reduced size, as shown in Fig. 3 adjacent one of the side walls 11a of the outer horn 11. By this construction of the tone chamber a material improvement in the quality of tone reproduction is obtained. Inclined wall 10 reduces the area of the outlet 10a of the horn and controls the bass notes, tending to increase their volume without any tremendous increase in force. The slanting disposition of wall 10 operates to reflect the tone waves against the left hand wall 11a. The opening 10a which is reduced in cross sectional area as compared with the cross sectional area of the horn modifies the tone and reduces the surface noise of the record caused by friction of the needle in the sound track of the record, thereby operating to greatly improve the quality of the reproduction of the recorded tones.

As shown in Figs. 5 and 6, I may provide a modified form of my invention with the reproducer arm disposed in the same relative position in the cabinet as shown in Fig. 1 but with the horn 9c extending from the reproducer arm parallel with the front wall of the cabinet and thence the portion 9 of the tone arm extending along the left hand side wall of the cabinet, and thence the

portion of the tone arm extending to its termination adjacent the central portion of the rear wall of the cabinet, with the inclined wall 10 in reversed position from that shown in Fig. 1, or in other words, in a reversed disposition of the horn from that shown in Fig. 1 and with a consequently longer tone arm due to the arrangement as described. An advantage that is obtainable by such construction is that as a result of the provision of such a longer tone arm, increased volume of tone would be reproduced. In this form of the invention as well as in the forms shown in Figs. 1 to 3, the end 10b of the inclined wall 10 is relatively close to the end 10c of the curved end portion 9b of the horn, thus providing a restricted opening 10a which is only about one-half the cross sectional area of the portion 9a of the horn. The purpose of this restricted opening and disposition of inclined wall 10 is to reduce the blasting effect of bass notes and to produce a better tone quality without any noticeable reduction in the volume of the tone.

What I claim is:

1. In combination with a portable phonograph having a turntable, reproducer, reproducer arm, motor board and portable cabinet, a tone arm in communication with the reproducer arm and positioned beneath and concealed by the motor board, said motor board forming the top wall of the tone arm, said tone arm extending parallel with the side of the phonograph adjacent to which the reproducer arm is mounted and curving near the rear of the cabinet and thence extending parallel with the rear of the cabinet and gradually expanding in cross-sectional area but terminating in an opening of reduced size at the surface of the motor board, a slightly upwardly inclined wall extending from the surface of the motor board and reducing the cross-sectional area of the opening of the horn from beneath the motor board to modify the tone of bass notes, a tone-modifying horn positioned over the aforesaid opening and above the motor board and supported thereon and comprising an upwardly and forwardly curved rear wall continuing forwardly as a horizontal top wall and disposed parallel with the motor board and extending only part way over the turntable to prevent interference with the reproducer arm, and outwardly expanding side walls on which said top wall is supported and which in turn are mounted on the motor board, the motor board forming the bottom wall of said horn.

2. In combination with a portable phonograph having a turntable, a reproducer, a reproducer arm, a motor board, and a portable cabinet, a tone arm positioned directly beneath and concealed by the motor board and in communication at one end with the reproducer arm and terminating in an opening at the surface of the motor board at the rear portion thereof, an upwardly inclined wall extending from the surface of the motor board to reduce the cross-sectional area of the aforesaid opening and to reflect and modify the tone, a horn positioned over said opening and above the motor board and supported thereon, said horn comprising an upwardly and forwardly curved rear wall continuing forwardly as a horizontal top wall disposed parallel with the motor board but extending only part way over the turntable to prevent interference with the reproducer arm, an outwardly extending side wall on which said top wall is supported, the motor board forming the bottom wall of said horn.

3. In combination with a portable phonograph

having a turntable, a reproducer, a reproducer arm, a motor board, and a portable cabinet, a horn positioned beneath and concealed by the motor board and having the underside of the motor board as its top wall, said horn having an inclined wall extending slightly upward above the surface of the motor board and reducing the size of the opening of the horn and reflecting the tone waves, a horn mounted over said opening and above the motor board and supported thereby and comprising an upwardly and forwardly curved rear wall continuing forwardly as a horizontal top wall and extending only part way over the turntable, outwardly expanding side walls on which said top wall rests, the side walls resting on the motor board, and the motor board forming the bottom wall of said visible horn.

4. In combination with a portable phonograph having a turntable, reproducer, reproducer arm, a motor board, and a phonograph cabinet, a tone arm in communication with the reproducer arm and disposed beneath the motor board and extending parallel with one side of the phonograph cabinet and curving at the rear and thence extending parallel with the rear of the cabinet, the motor board forming the top wall of the said tone arm, said tone arm gradually expanding in cross-sectional area and extending a short distance above the surface of the phonograph motor board and terminating in an opening of reduced cross-sectional area, an upwardly and forwardly curved wall extending over the open end of the aforesaid tone arm and continuing forward horizontally and extending part way over the turntable, expanding side walls on which said top wall is secured, said side walls being mounted on the motor board and the motor board forming the bottom wall of the portion of the horn visible above the motor board, whereby to increase the volume of tone and improve the tone quality.

5. In combination with a phonograph of the type described, having a turntable, a reproducer, a reproducer arm, a motor board, and a portable cabinet, a tone arm having one end in communication with the reproducer arm and positioned beneath the motor board and extending around the front, thence adjacent one side wall and thence adjacent a portion of the rear wall to approximately a middle plane of the cabinet, said tone arm expanding in cross-sectional area, an upwardly inclined wall extending from the surface of the motor board part way over the opening of said horn to reduce its cross-sectional area and to reflect the tone waves, and a horn positioned over said opening and on the motor board, said horn comprising a forwardly and upwardly curved wall continuing in a horizontal top wall, expanding side walls to which said top wall is secured, the side walls being mounted on the motor board, and the motor board forming the bottom wall of the said visible horn.

6. In combination with a portable phonograph having a turntable, a reproducer, a reproducer arm mounted at one front corner of the instrument, a motor board, a portable cabinet, a tone arm positioned and concealed beneath the motor board and in communication with the reproducer arm, said tone arm extending parallel to the front wall of the phonograph cabinet, thence curving and extending adjacent a side wall of the cabinet and thence curving and extending one-half way across the rear of the cabinet adjacent the rear wall, an upwardly slanting wall extending from the surface of the motor board part way across the mouth of the concealed tone arm and

functioning to reduce the cross-sectional area of the mouth of said tone arm and to modify the tone waves, a visible horn mounted above the surface of the motor board and over the mouth of the tone arm and comprising opposite like expanding side walls extending only part way past the turntable, a top wall mounted on the side walls, and having a rear curved portion extending over the opening of the tone arm which functions to improve the tone quality and increase its volume without interfering with the reproducer arm, the motor board forming the bottom wall of said visible horn.

7. In combination with a phonograph of the type described having a turntable, a reproducer, a reproducer arm, a motor board, and a portable cabinet and hinged cover, a tone arm of expanding size with its small end in communication with the reproducer arm and positioned beneath the motor board and having the other end terminating in an opening of reduced size at the surface of the motor board, the motor board forming the top wall of said tone arm, an upwardly inclined wall extending from the surface of the motor board part way over the mouth of the tone arm, said opening being of reduced cross-sectional area relative to the cross-sectional area of the adjacent portion of the tone arm to reduce the reproduction of surface noises due to friction of the needle on the record, and an exteriorly positioned horn positioned above the motor board and over

said tone arm mouth, said horn comprising expanding side walls and a top and rear wall secured to said side walls and positioned slightly below the inner surface of the cover of the phonograph, the motor board forming the bottom wall of said horn, said horn improving the tone quality and increasing its volume.

8. In combination with a phonograph, having a conventional turntable, reproducer, and reproducer arm, a motor board, a horn positioned directly beneath the phonograph motor board and extending parallel to the adjacent side of the motor board and curving at the rear and thence extending parallel with the rear of the cabinet and gradually expanding in cross-sectional area and terminating in a reduced size opening at the surface of the phonograph motor board, an upwardly inclined wall extending part way over the aforesaid open end of said horn to reflect and modify the tone waves, a horn mounted above the phonograph motor board and over said opening and comprising an upwardly curved rear wall continuing forwardly as a horizontal top wall disposed parallel with the motor board but extending only part way over the turntable so as not to interfere with the reproducing arm, and outwardly expanding side walls of uniform width resting on the motor board and on which said top wall is supported.

RICHARD HAL COFFREN.
